UNITED STATES PATENT OFFICE.

HERMAN O. GOTTESMAN, OF NEW YORK, N. Y.

EMERGENCY UMBRELLA.

Application filed September 14, 1927. Serial No. 219,385.

This invention relates to improvements in so called emergency umbrellas of the sort folded from waterproof paper and intended to be retailed at a very low price at newsstands, cigar stores and other convenient points where a person caught in a sudden shower may avail himself of such a protective covering and then discard it when the emergency has passed.

10 Umbrellas of the emergency type have already been devised, but they have all been open to the same objection, that they were costly to manufacture and consequently could not be offered at a price which would 15 make the proposition attractive as an emergency article. It might be mentioned that the prohibitive costs of the umbrellas heretofore manufactured were due largely to the great number of parts constituting each article, each part taking its toll in material and labor, in the course of both manufacture and assembly.

20 With the foregoing in mind it is the purpose of the present invention to provide an emergency umbrella which will consist of the minimum number of parts, and which, while it will be self sustaining, at the same time will be sufficiently durable to withstand the elements. I accomplish this purpose by 25 means of the construction and combination of parts described in detail in the following specification and claims and illustratively exemplified in the accompanying drawings, in which, Figure 1 is a plan view of my improved emergency umbrella shown in open 30 position; Figure 2 is a substantially transverse sectional view of the same taken on lines 2—2 of Figure 1, Figure 3 is a plan view of one end of the scored blank from 35 which the cover is folded; Figure 4 is a side view of the blank in folded position and the connecting means shown in section; Figure 40 5 is an enlarged sectional view of the cover, connecting means and stick; Figure 6 is a plan view of the same, and Figure 7 is a modified embodiment of connecting means and adjacent portion of the cover.

45 Referring to the drawings, the three elements of the invention are designated generally as follows, A denotes the paper covering, B, the connecting means and C the stick.

The covering A is folded from a substantially straight strip of flexible material 10, preferably a fairly stout waterproof paper, 55 which is divided into a number of substantially rectangularly shaped areas 11 by a plurality of equally spaced scored lines 12 disposed transversely of the strip 10, the material being folded along the lines 12 60 so as to form a plurality of plaits 13, which present a hill and dale appearance when the umbrella is in open position as shown in Figures 1 and 2 particularly. The material of the strip 10, at what becomes the 65 periphery of the covering A, is reinforced by scored lines 14 which are disposed at an angle to the lines 12 and adjacent end of the blank, the lines 14 being further disposed alternately so that alternate lines 12 70 bisect the apex of a triangular area 15 spanning two sides of a plait 13, as illustratively exemplified in Figure 3. When the material is in folded position as shown in Figure 4, the triangular area or gusset 15 folds 75 on itself along the line 12 and is disposed between two plaits 13, thereby leaving the outer end at an angle to the longitudinal axis of the plaits. When the covering is open as illustratively exemplified in Figure 1 80 the gussets 15 straighten out and form an outward bevel for each ridge formed by the plaits. An important characteristic of the plaits 13 according to my invention, is that each is substantially rectangularly shaped 85 and as a consequence is practically of an equal depth throughout its length when folded and affords a substantial width of material at its inner end to which the connecting means B may be attached and carried. To facilitate the installation of connecting means B, and to give a slight conical shape to the open covering, the inner end of 90 each plait 13 is cut at a slight angle in the direction of the score line 14 at the opposite or outer end, so that when the covering is collapsed, as shown in Figure 4, the inner ends will all be parallel and in superimposed position. A T-shaped slot 16 is punched 95 through the layers of plaits, the cross portion being disposed parallel to and spaced short of the end of the material while the stem portion opens out of the end. The effect produced by the slot 16 is clearly illus-

trated in Figure 3. The covering is opened by unfolding the material in a circle and attaching the opposite ends or plaits 13 together. To facilitate this operation I form 5 the plait 13^a at one end without the slot 16 so that it may be inserted between the walls of the end ridge and a suitable fastening means 17 used to fix the connection.

Referring now to the connecting means B, 10 the latter comprises a hub or short length of tubing 17 preferably of cardboard which has its ends inserted through the stem portion of the slot 16 into the cross portion, as illustrated particularly in Figure 4. This 15 arrangement brings the tabs 16^a of material, on opposite sides of the stem portions of the slots 16, within the cylinder or tube 17, permitting the latter to act as a guide during the opening operation of the cover, which 20 naturally unfolds about the tube as an axis. With reference to Figure 6, it will be clear that the said tabs 16^a arrange themselves in irislike formation about the inner wall of the tube 17, so as to enable the stick C to 25 be inserted therebetween.

The stick C is simply a straight length of full round material, preferably wood or cardboard tubing having a slightly reduced end 18 which is adapted to be inserted into 30 the tubing 17 between the inner ends of the plaits when the covering is opened for use. It has been found that the end 18 of the stick is firmly gripped by the material at 35 the opening so as to enable the umbrella to withstand considerable strain without its pulling off of the stick or handle.

In the modification of the connecting means illustratively exemplified in Figure 7 the ends of the plaits 13 are merely provided 40 with straight slots 18 parallel to and spaced short of the inclined inner edges, the latter being inserted into the interior of the tube 19 through a longitudinal slot 20 disposed throughout the length of its wall.

45 When the invention is arranged for sale the cover A is a flat proposition carrying the connecting means B at one end, as shown in Figure 4. The cover A is then placed in an envelope just large enough to accommodate 50 it and the stick C which is of a length equal to the length of covering when folded.

To erect the umbrella, the folded cover material 10 is swung about the tubing 17 until the end plait 13^a is arranged over the 55 ridge at the opposite end whereupon a fastener is inserted. The result is a large circular cone, comprising a plurality of radially disposed ribbed folds forming drainage spaces running to the periphery of the covering and of substantially decreasing depth as they approach the said periphery. The reduced end 18 of the stick C is then 60 inserted through the tube 17 from underneath and firmly gripped by the tabs 16^a disposed within the tube.

Having now described the nature of my invention what I claim and desire to obtain by Letters Patent is:

1. An umbrella having a cover comprising a plaited strip of material and connecting 70 guide means for one side of the strip about which means the material is rotatably unfolded to open position.

2. An umbrella having a cover comprising a plaited strip of material, connecting 75 guide means for one side of the strip about which means the material is rotatably unfolded to open position, and a stick removably inserted in said means.

3. An umbrella having a cover comprising 80 a plaited strip of material slotted at spaced intervals along one longitudinal edge, a cylindrical member projecting through said slots about which member the cover is rotatably unfolded to open position, and a stick 85 removably inserted in said member.

4. An umbrella having a cover folded from a blank comprising a straight strip of material provided with substantially parallel spaced score lines disposed transversely 90 of the length of the blank, the spaces between the score lines being provided with a T-shaped slot at the end forming the center of the cover, a tubular connection and guide projecting through said slots about which 95 guide the plaits are unfolded in a rotary direction to form a circular device, and a stick insertable into said tubular connection, the portion of the cover material beyond the said slots being wedged between the stick and the 100 interior wall of the tubular connection.

5. An umbrella comprising a body portion having a series of radially ridged portions forming gutter like drainage spaces therebetween, the ridges in service being contracted 105 adjacent the center of said body portion and progressively expanded toward the periphery thereof, a guide member insertable in said radial ridged portions and about which the latter is unfolded in rotary direction to 110 open position, and a stick insertable in said member.

6. An umbrella having a cover portion folded from a blank of straight material which is scored along spaced parallel lines 115 disposed transversely of the blank and angularly arranged scored lines along one side of the blank, alternate parallel scored lines bisecting the apices of the angular lines, whereby when the cover is unfolded in a 120 circular path there is a series of radially rigid portions forming gutter like drainage spaces and a similar number of gussets at the periphery of the ridges, each space between said parallel scored lines being cut 125 off at an angle at the side opposite the angular scored lines and provided with T-shaped slots adjacent said ends cut at an angle, a tubular connecting guide projecting through said slots, about which guide the radially 130

ridged portions unfold in a rotary direction, and a stick insertable in said tubular piece and against the material of the cover beyond the said slots.

- 5 7. An umbrella having a cover creased to provide a plurality of rectangular plaits, slots in the inner ends of said plaits disposed

at an angle to both the transverse and longitudinal axes thereof, a tubular hub projecting through said slots, about which guide 10 the plaits unfold in a rotary direction to form a cone shaped covering.

In testimony whereof I affix my signature.

HERMAN O. GOTTESMAN.
